UNITED STATES PATENT OFFICE.

WILLIAM HUBELI WALDRON, OF NEW BRUNSWICK, NEW JERSEY,
ASSIGNOR TO JOHN WALDRON COMPANY, OF NEW BRUNSWICK,
NEW JERSEY.

REGISTERING DEVICE FOR PRINTING-MACHINES.

No. 805,172.

Specification of Letters Patent.

Patented Nov. 21, 1905.

Application filed December 8, 1904. Serial No. 236,012.

To all whom it may concern:

Be it known that I, WILLIAM HUBELI WALDRON, a citizen of the United States, and a resident of New Brunswick, in the county of 5 Middlesex and State of New Jersey, have invented a new and Improved Registering Device for Printing-Machines, of which the following is a full, clear, and exact description.

The invention relates to wall-paper-printing machines, and more particularly to such machines in which the paper is run two or more times through the machine for successive impressions.

The object of the invention is to provide a new and improved registering device for multicolor-printing machines, arranged to permit a quick, convenient, and easy adjustment of the printing-rolls relative to the impression-cylinder to insure an accurate registering of 20 the printing-rolls with a previous impression on the paper.

The invention consists of novel features and parts and combinations of the same, as will be more fully described hereinafter and then 25 pointed out in the claims.

A practical embodiment of the invention is represented in the accompanying drawings, forming a part of this specification, in which similar characters of reference indicate corresponding parts in all the views.

Figure 1 is a side elevation of a printing-machine provided with the improvement, parts of the printing-machine non-essential to the working of the improvement being omitted. 35 Fig. 2 is an enlarged sectional plan view of the improvement. Fig. 3 is a cross-section of part of the same on the line 33 of Fig. 2; and Fig. 4 is an end elevation of the improvement as applied, minor parts of the printing-machine being omitted.

The impression-cylinder A and the printing-rolls B of a multicolor-printing machine are mounted in the usual manner and their supports carried on the main frame C, and on 45 the shaft A' of the impression-cylinder A is secured a gear-wheel A² in mesh with a pinion A³, secured on a shaft A⁴, provided with a driving-pulley A⁵, connected with other machinery to rotate the shaft A⁴ and the impression-cylinder A. (See Fig. 4.) On the shaft A⁴ is secured a pinion A⁶, geared with a gear-wheel A⁷, journaled on a stud A⁸, carried by the frame C, and this gear-wheel drives the color-

aprons in the usual manner, so that further description of this portion of the machine is 55 not deemed necessary.

A gear-wheel F for driving the printing-rolls B is journaled on a stud F', held on the frame C, and this gear-wheel F is in mesh with a pinion D, mounted to rotate loosely on 60 a sleeve E, secured on the shaft A⁴ above mentioned.

On the hub of the pinion D is formed or secured a worm-wheel D' in mesh with a worm G, the shaft G' of which is journaled in suitable bearings E', secured to a flange E² integral with the sleeve E, so that when the color-printing machine is in motion and the shaft A⁴ rotates then the sleeve E rotates with the shaft A⁴, and as the sleeve E and the pinion 70 D are locked together by the worm-wheel D' and the worm G it is evident that the pinion D is rotated to drive the gear-wheel F and the printing-rolls B. On one end of the sleeve E is secured a sprocket gear-wheel H, 75 connected by a sprocket-chain H' with a sprocket-wheel H², secured to the hub of a bevel gear-wheel I, (see Fig. 2,) mounted to rotate loosely on a transversely-extending shaft J, journaled in suitable bearings on a 80 frame K, which may form part of the main frame C or be separate therefrom. The bevel gear-wheel I is in mesh with one side of an intermediate bevel gear-wheel I', mounted on a shaft I² and in mesh at the other side with 85 a bevel gear-wheel I², secured to the shaft J, the outer end of which is connected by a spur-wheel J' with a spur-wheel J², secured on a shaft J³, parallel to the shaft J, and likewise journaled in suitable bearings on the frame 90 K. On the shaft J³ is secured a sprocket-wheel L, connected by a sprocket-chain L' with a sprocket-wheel L², secured to the hub of a bevel gear-wheel N, mounted to rotate 95 loosely on the sleeve E adjacent to the sprocket-wheel H. The bevel gear-wheel N is in mesh with a bevel gear-wheel N', mounted to rotate loosely on a stud N², projecting from the sleeve E, and on one face of the bevel gear-wheel N' is secured or formed a 100 spur-wheel N³, in mesh with a pinion N⁴, secured to the shaft G' of the worm-wheel G.

When the sleeve E rotates, as previously described, the rotary motion is transmitted to the bevel gear-wheel I by the sprocket-wheels H H² and the sprocket-chain H', and

the rotary motion of this bevel gear-wheel I is transmitted by the bevel gear-wheel I' to the bevel gear-wheel I² to rotate the shaft J in unison with the sleeve E, the rotary motion of the shaft J being transmitted by the gear-wheels J' J² to the shaft J³, so that the latter rotates at the same speed as the shaft J. The rotary motion of the shaft J³ is transmitted by the sprocket-wheels L L² and 10 sprocket-chain L' to the bevel gear-wheel N to rotate the latter at the same rate of speed as the sleeve E and in the same direction. Now when the machine is running and the sleeve E is rotated, as described, then the bevel gear-wheel N', spur-wheel N³, and pinion N⁴ are bodily carried around by the said sleeve, and as the bevel gear-wheel N is rotating in unison with the sleeve it is evident that the bevel gear-wheel N', spur-wheel N³, 20 and pinion N⁴ do not turn on their axes, and hence the worm G is not rotated, and it and the worm-wheel D' simply act as a locking device to lock the pinion D to the sleeve E for the pinion to rotate with the sleeve and 25 to drive the printing-rolls B.

In order to turn the pinion D on its sleeve E in either a forward or backward direction to set the printing-rolls B ahead or backward with a view to obtain accurate registration 30 with the impressions already on the paper now run a second time through the machine, the following device is provided: The shaft I³ of the intermediate bevel gear-wheel I' is journaled radially in the web of a sprocket-wheel O, mounted to rotate loosely on the shaft, (see Figs. 1 and 2,) and this sprocket-wheel O is connected by a sprocket-chain O' with a sprocket-wheel O², secured on a shaft O³, journaled on the main frame C, and provided with a hand-wheel O⁴, under the control of the operator, for turning the said sprocket-wheel O² in either direction to cause the chain O' to correspondingly turn the sprocket-wheel O. Ordinarily the sprocket-wheel O² is at a standstill and is only rotated forward or backward by the operator manipulating the wheel O⁴ whenever it is necessary to give additional movement to the printing-rolls with a view to obtain accurate registration, as above described. By turning the sprocket-wheel O² in a forward direction the intermediate bevel gear-wheel I' is carried bodily along, and in doing so it rotates the sprocket-wheel I² correspondingly faster than 45 the sprocket-wheel I, and in case the sprocket-wheel O² is turned in the reverse direction then the sprocket-wheel O is similarly turned and the intermediate bevel gear-wheel I' is carried bodily backward, and thereby imparts 50 a speed to the sprocket-wheel I² less than that of the sprocket-wheel I. As the sprocket-wheel I is secured on the shaft J and the latter is geared to the worm-wheel shaft G', as previously explained, it is evident that the worm 55 G is rotated either forward or backward to

give an additional turning movement to the worm-wheel D' and the pinion D—that is, to increase the latter's speed or to reduce it relative to the shaft A⁴, the impression-cylinder A, and the surface speed of the paper on which the impression is to be made by the printing-rolls B, driven from the said pinion D. Thus the printing-rolls B are shifted forward or backward the desired distance until accurate registration of the printing-rolls with the previous impression on the paper is had.

It is understood that by the arrangement described the shaft A⁴ drives the gearing and the gearing is controlled by the manually-operated hand sprocket-wheel to increase or decrease the speed of the pinion D to shift the printing-rolls forward or backward for the purpose described. It is further understood that the sprocket-wheels H H², sprocket-chain H', and bevel gear-wheel I is the driving portion of the gearing driven from the shaft A⁴, while the bevel gear-wheel I², shaft J, gear-wheels J' J², shaft J³, sprocket-wheels L L², sprocket-chain L', bevel gear-wheels N N', spur-wheel N³, pinion N⁴, worm G, and worm-wheel D' form a return-gearing for rotating the pinion D at an increased or retarded speed to shift the printing-rolls simultaneously, and, according to the desires of the operator, manipulating the sprocket hand-wheel 90 in order to bring the printing-rolls in accurate register with the impression already on the paper.

It is understood that by subjecting the paper to an impression and drying it the paper shrinks unevenly, and hence when the paper with its first impression thereon is run a second time through the machine it is evident that the printing-rolls B are almost constantly out of register with the previous impression. By the arrangement described the operator in charge constantly watches the second impression, and if the second impression is out of register with the first one he simply turns the hand-wheel O⁴ correspondingly forward or backward until the printing-rolls B run in register with the first impression.

By the arrangement described a most minute adjustment of the printing-rolls relative to the first impression on the paper can be had without much exertion on the part of the operator, as the gearing described is driven from the shaft A⁴ and is controlled by the operator.

Having thus described my invention, I claim as new and desire to secure by Letters Patent—

1. In a printing-machine, the combination of the impression-cylinder with the printing-rolls, a driven shaft geared with the impression-cylinder, a sleeve secured on the said shaft, a gearing positively driven from the said sleeve and having a return-gearing, and a driving and locking gear driven from the said return-gearing, mounted on the said sleeve and having a shiftable pinion loose on the sleeve and geared with the printing-rolls.

2. In a printing-machine, the combination of the impression-cylinder with the printing-rolls, a driven shaft geared with the impression-cylinder, a sleeve secured on the said shaft, a gearing positively driven from the said sleeve and having a return-gearing, a driving and locking gear driven from the said return-gearing, mounted on the said sleeve and having a shiftable pinion loose on the sleeve and geared with the printing-rolls, and a manually-controlled wheel, in the web of which is journaled the driving gear-wheel of the said return-gearing.
- 5 In testimony whereof I have signed my name to this specification in the presence of two sub- 30
scribing witnesses.
- 10 WILLIAM HUBELI WALDRON.
- 15 Witnesses:
3. In a printing-machine, the combination of the impression-cylinder with the printing-rolls, a driven shaft geared with the impres-

sion-cylinder, a sleeve secured on the said shaft, a gearing positively driven from the 20
said sleeve and having a return-gearing, a driving and locking gear driven from the said return-gearing, mounted on the said sleeve and having a shiftable pinion loose on the sleeve and geared with the printing-rolls, and a 25
manually-controlled wheel, in the web of which is journaled the driving gear-wheel of the said return-gearing.

In testimony whereof I have signed my name to this specification in the presence of two sub- 30
scribing witnesses.

WILLIAM HUBELI WALDRON.
